CLAIM

The ornamental design for a lighting fixture, as shown and described.

DESCRIPTION

FIG. 1 is a perspective view of a lighting fixture showing our new design;

FIG. 2 is a top view thereof;

FIG. 3 is a bottom view thereof;

FIG. 4 is a side elevation view thereof;

FIG. 5 is a side elevation view thereof;

FIG. 6 is a front elevation view thereof; and,

FIG. 7 is a back elevation view thereof.

The broken lines shown in the drawings illustrate portions of the lighting fixture that form no part of the claimed design.
